UNITED STATES PATENT OFFICE.

ALFRED G. CASH, OF ROCHESTER, NEW YORK.

TEST-INDICATOR.

1,235,551.

Specification of Letters Patent.

Patented Aug. 7, 1917.

Application filed December 23, 1916. Serial No. 138,624.

To all whom it may concern:

Be it known that I, ALFRED G. CASH, a citizen of the United States, and resident of Rochester, in the county of Monroe and 5 State of New York, have invented certain new and useful Improvements in Test-Indicators, of which the following is a specification.

The present invention relates to test indicators for indicating to a workman the amount to be removed from a work piece in order to obtain a desired surface, an object of this invention being to provide a construction in which the contact element may 10 be moved in either direction to produce a movement of the indicating finger in one direction from its normal position without necessitating any adjustment of the internal parts of the instrument.

20 To this and other ends, the invention consists of certain parts and combinations of parts all of which will be hereinafter described, the novel features being pointed out in the appended claims.

25 In the drawings:—

Figure 1 is a view of one embodiment of the invention with the cover plate removed and the indicating finger lying in a certain normal position;

30 Fig. 2 is a view similar to Fig. 1, showing the indicating finger moved to its extreme adjusted position by pressure on the contact finger in the direction of the arrow;

Fig. 3 is a view similar to Fig. 2, showing 35 the indicating finger adjusted to extreme position by pressure on the contact element in the opposite direction;

Fig. 4 is a longitudinal sectional view through the instrument;

40 Fig. 5 is a transverse sectional view on the line 5—5, Fig. 4;

Fig. 6 is a front view of another embodiment partially broken away to show the interior;

45 Fig. 7 is a partial longitudinal sectional view through the instrument shown in Fig. 6;

Fig. 8 is a view similar to Fig. 1 of still another embodiment of the invention; and

50 Fig. 9 is a detail view showing a still further embodiment of the invention.

Referring first to the embodiment shown in Figs. 1 to 5, there is employed a base plate 1 which gradually widens from one end 55 to the other and is supported in any suitable manner, as by a stud 2. This base plate has

side flanges 3 which support a cover 4 held in place by screws 5. At one end of the base plate 1, a scale 6 is arranged, the cover being shorter than the base plate so as to 60 expose the scale and the indicating finger or pointer 7 which operates over the scale, this indicating finger or pointer being in the form of an arm extending from a pivoted part 8 which turns about an axis 9. 65

At the opposite end of the base 1, a contact element 10 projects, said element being preferably pivoted to turn on a stud 11 and adjustably connected to a pivoted part 12. The connection in this instance is in the 70 form of a bifurcation in the contact element, having its arms connected by a sleeve 13 which is surrounded by the pivoted part 12 and a friction washer 14, this adjustment permitting the contact element to be shifted 75 laterally in either direction, with reference to the pivoted part 12, by exerting a certain pressure on the contact element. Under ordinary conditions, the pivoted part 12 and the contact element are held in frictional engagement, so that the pivoted part 12 partakes of the movement of the contact element 10. 80

The connection between its pivoted parts 8 and 12 is such that the movement of the pivoted part 12 in either direction causes the pivoted part 8 to turn in one and the same direction from a certain normal position where it is held by the spring 15 in a manner to be hereinafter described. In this embodiment, the part 8 is provided with two lateral projections 16 and 17 arranged on opposite sides of the pivot 9, the projection 16 being a slightly greater distance from the pivot 9 than is the projection 17, and said 90 projection also being so located that one face of one of the projections 16 is in alinement with the central line through or the longitudinal axis of the pointer finger, while the opposite face of the projection 17 is in alinement with said central line of action, said faces providing two points of engagement. The pivoted part 12 has one end bent or deflected at 18 on one side of its pivot 11 so that said end lies between the projections 16 and 17, and provides two points or surfaces 19 and 20 at different distances from the pivot 11, for coöoperating, respectively, with the points of engagement or projections 16 and 17. The spring 15 before mentioned is preferably in the form of an arm anchored at 21 100 and having its free end bearing against the

105

110

projection 17, so that the indicating finger or pointer 7 is normally held in a certain position at one end of the scale 6.

It will be apparent that pressure in the direction of the arrow in Fig. 2 will cause the point of engagement 19 to bear upon the projection 16 and swing the pointer or indicating finger 7 to the right against the action of the spring 15, while pressure on the contact element 10 in the direction of the arrow, Fig. 3, will cause the point of engagement 20 to bear against the projection 17 and swing the indicating finger in the same direction as it is swung by the engagement 15 between the point 19 and the projection 16.

In the use of the device the zero point of the scale indicates that the work is correct. In this position of the pointer the contact finger is engaged with the work and the 20 spring is under tension. If too much material has been removed from the work at any point, the pointer will shift in one direction, whereas, when more material is required to be removed from any point, the pointer will 25 shift in the other direction.

In the embodiment shown in Figs. 6 and 7, the parts are the same except that the indicating pointer 7^a is mounted upon a spindle 22 which is journaled in the base 1^a and 30 carries a pinion 23, which, in turn, is engaged by a segmental gear 24 extending from the pivoted part 8. The scale 6^a, instead of being formed upon the base 1^a, is arranged upon a disk supported at its edges in spaced relation 35 to the base 1^a, said pointer and disk being covered by a crystal 25 held in place by a ring 26. This embodiment provides for a greater movement in the indicating finger and thus gives a wider range of reading.

40 In the embodiment shown in Fig. 8, the parts are the same as in Fig. 1, except that the pivoted part 12 has two fingers 19^a and 20^a at one side of its pivot, one of said fingers coöperating with the projection 16, and 45 the other of said fingers coöperating with the projection 17 on the pivoted part 8. The operation of this device is the same as those shown in Figs. 1 to 7.

Instead of providing two projections on 50 the pivoted part 8, as shown in Figs. 1 to 8, two projections 19^b and 19^c may be provided on the pivoted part 12, and the pivoted part 8 may extend between these projections and be provided with two points of engagement 55 16^a and 17^a, on opposite sides of its pivot 9, the spring 15 in such instance having its end fitting in a slot 27 formed in the member 8.

In all embodiments of the invention, a connection is provided between the contact 60 element and the indicating finger which has provision whereby, on a movement of the contact element, in either of two opposite directions, the indicating finger is moved from a certain normal position against the 65 action of a spring, preferably by providing

two pivoted parts in the connection, each of said parts having two points of engagement coöperating with the points on the other part, one pair coöperating when the contact element is moved in one direction, and the other pair coöperating when the contact is moved in the opposite direction. 70

What I claim as my invention and desire to secure by Letters Patent is:—

1. In an instrument of the class described, 75 a contact element, an indicating finger, a spring for maintaining the finger in a certain position, and connecting means between the contact element and the indicating finger having provision for moving the 80 finger away from the certain position in one and the same direction on a movement of the contact element in either of two opposite directions.

2. In an instrument of the class described, 85 a contact element, an indicating finger, a spring for maintaining the finger in a certain position, and connecting means between the contact element and the finger embodying two parts, one having two points of engagement either of which when engaged moves the finger in one and the same direction from the certain position, and the other being arranged to engage one of said points when the contact element is moved in one 90 direction and the other of said points when the contact element is moved in the other direction. 95

3. In an instrument of the class described, 100 a contact element, an indicating finger, a spring for maintaining the finger in a certain position, and connecting means between the contact element and the indicating finger embodying two parts each provided with two points of engagement, one of said points 105 of engagement on one part coöperating with a corresponding point on the other part when the contact element is moved in one direction to move the finger away from the certain position, and the other two points of engagement coöperating when the contact element is moved in the opposite direction to move the finger away from the certain position in the direction in which it was moved by the coöperation of the first mentioned points of engagement. 115

4. In an instrument of the class described, 120 a contact element, an indicating finger, a spring for maintaining said finger at a certain position, and connecting means between the contact element and the indicating finger comprising two pivoted parts, one of which has two projections thereon lying on opposite sides of the pivot of the part by which it is carried, and the other of which carries 125 two points for coöperating with said projections, one point with one side of one of said projections, and the other point with the opposite side of the other projection.

5. In an instrument of the class described, 130

- a contact element, an indicating finger, a spring for maintaining said finger at a certain position, and connecting means between the contact element and the indicating finger 5 comprising two pivoted parts, one of said parts having two points of engagement on opposite sides of its pivot, one of said points of engagement being situated a greater distance from the pivot than the other, and 10 the other of said parts having two points of engagement situated on one and the same side of the pivot of said part, one being arranged further from the pivot than the other and coöperating with that point on 15 the other part which is situated a greater distance than the pivot of said other part, the coöperation being such that when the contact member is moved in one direction, one pair of coöperating points shifts the indicating finger away from its normal position, and when the element is moved in the 20 opposite direction, the other pair of coöperating points shifts the indicating finger in the same direction away from normal position.
6. In an instrument of the class described, a contact element, an indicating finger, a spring for maintaining the finger in a certain position, and connecting means between 25 the contact element and the indicating finger comprising two pivoted parts, one of which is provided with two projections, and the other of which has a portion extending between the projections and is provided with 30 two points of engagement for coöperating
- with said projections, one of said pivoted parts having its pivot located between the points of engagement thereof, and the other of said pivoted parts having its pivot located to one side of the points of engagement thereof. 40
7. In an instrument of the class described, a contact element, an indicating finger, a spring for maintaining the finger in a certain position, and connecting means between 45 the contact element and the indicating finger embodying two pivoted parts, one of which is provided with two projections on opposite sides of the pivot thereof, and the other of which is provided with two points of engagement located at different distances from the pivot of said parts, one of said points coöperating with one side of one projection, and the other of said points coöperating with the opposite side of the other 50 55 projection.
8. In an instrument of the class described, a contact element, an indicating finger, a spring for maintaining the finger in a certain position, and connecting means between 60 the contact element and the indicating finger embodying two pivoted parts, one of which has two projections extending therefrom on opposite sides of the pivot, and the other of which has a curved portion to one side 65 of its pivot, extending between the projections to coöperate with one face of one projection and the opposite face of the other projection.

ALFRED G. CASH.
